MUSICAL INSTRUMENT CASE

Rundlette K. Palmer, P.O. Box 69, Newcastle, Maine

Filed Feb. 4, 1964, Ser. No. 78,519

Term of patent 14 years

(Cl. D56—1)

FIG 1

The end of the musical instrument case not shown is substantially the same as the end view shown in FIGURE 5.

I claim:

The ornamental design for a musical instrument case, as shown and described.
